UNITED STATES PATENT OFFICE.

PATRICK B. DELANY, OF SOUTH ORANGE, NEW JERSEY, ASSIGNEE TO THE TELEPOST COMPANY, OF NEW YORK, N. Y., A CORPORATION OF MAINE.

TELEGRAPHY.

1,124,598.

Specification of Letters Patent. Patented Jan. 12, 1915.

Application filed December 23, 1906. Serial No. 480,660.

To all whom it may concern:

Be it known that I, PATRICK B. DELANY, a citizen of the United States of America, residing in South Orange, in the county of 5 Essex and State of New Jersey, have invented certain Improvements in Telegraphy, of which the following is a specification.

The invention relates more particularly to 10 automatic transmission, and chemical recording in a local circuit controlled by relays in a main circuit, and is more especially designed for the distribution of news among a plurality of way stations, although ordinary traffic can be carried on in the same 15 way and with an important increase of a wire's facilities.

The main features of the system described 20 herein provide for automatic transmission with double current or reversals, to polarized relay receivers that control the recording circuits which are local; or transmission may be effected with single current to neutral relays controlling the same recording 25 circuits, and way stations may transmit automatically without the use of local main batteries simply by inserting an automatic transmitter in the line. Normally the various stations are connected to the circuit by the ordinary sounder controlled by a Morse 30 relay.

As messages may be prepared on tapes by 35 perforations preliminary to their transmission and then transmitted at a comparatively high rate of speed, say from one hundred and twenty-five to one hundred and fifty words per minute, as against an average of from ten to fifteen words per minute between the way offices and the main office, or between two way offices as at present operated; the gain in carrying capacity and saving of time can easily be understood. For distribution of news thirty or forty offices may be connected in series to a single 40 wire, and as the record at each place is made by local current the marks may be made heavy and distinct without regard to line conditions. I have found, however, that even in a local circuit the chemical record may be greatly improved by reversals 45 of current, using two batteries. A simpler and even more effective way, however, of clearing the record from the "tailing" effect of whatever capacity there may be in the local circuit itself and also from local 50 electro-chemical action as well, lies in the

use of a source of induction in the local circuit placed as an electro-magnetic shunt around the contact points of the relay, so that when the local circuit is broken the induced current of opposite polarity from the 55 electro-magnetic shunt immediately follows the recording current. This action is much quicker than that obtained by a reversal of current from a source that cannot be effective until the armature lever of the relay 60 reaches its other contact. Another improvement consists of a switch at each station which, with a single movement, connects the installation for Morse or automatic transmission, for double current reception, or for 65 single current reception.

In the accompanying drawing: Figures 1, 2 and 3 taken together show diagrammatically the organization and operation of the invention—the three figures constituting one 70 diagram.

When switches S of station X Fig. 1, S' of station I Fig. 2, and S² of station Y Fig. 3 are in the first position (as illustrated) they are arranged for transmission by Morse 75 key K or polarized relay R'. The circuit is as follows; from positive pole of battery B through key K to switch s of recorder A, wire w, switch s' of transmitter T, wire y to contact a of switch S, wire w², neutral 80 relay N and wire w³ to line L; and then to neutral relay N' at station I, wire w⁴, contact a' of switch S', wire w⁵, switch s', wire w⁶, key K', wire w⁷ to line L; and then to neutral relay N², wire w⁸, contact a² of 85 switch S², wire w⁹, transmitter switch s², wire w¹⁰, recorder switch s², wire w¹¹, and Morse key K² to negative pole of battery B'. If Morse keys K' at I and K² at Y be closed, then key K at X will operate the circuit 90 Morse through neutral relays N, N', N². This completes the regular Morse circuit operated by sound in the ordinary way and with any desired number of way stations included. To send automatic, station X moves the lever of transmitter T, forward 95 until it is locked in its front position simultaneously with the grip of the rollers on the transmitting tape and the pressure of two fingered contact y on its upper face. The polarized relay R' is operated by reversals 100 of current from battery F. For double current automatic transmission switch S at X should remain as shown and switch S' at I, and S² at Y should be turned to the second 105 110

position provided stations I and Y are to receive the same message. With key K at station X closed and the negative battery switch of battery B also closed, the circuit will be as follows; from armature of polarized relay R' switch s' of transmitter T, wire y , contact a of switch S, wire w^2 , neutral relay N, wire w^3 to line L and polarized relay R^2 at station I, wire n , contact b' of switch S' , wire w^4 , switch s^2 of transmitter T', wire w^6 , key K', wire w^7 to line L, polarized relay R^4 at Y, wire w^{12} , contact b^2 of switch S^2 , wire w^9 , switch s^4 of transmitter T ^{2} , wire w^{10} , switch s^5 of receiver A ^{2} 15 and to earth E when the receiver lever is pushed forward.

At both stations, I and Y, the operation of receiving from reverse currents is as follows: The lever of recorder A' having been moved forward so as to put the chemically moistened tape in motion and to bring the recording wire down upon it, the arriving signals actuate polarized relay R^2 causing its armature to close circuit of battery w^2 20 through adjustable resistance r' , recording wire t' , chemical tape, wire w^{15} , contact d^2 of switch S' and wire w^{16} back to the armature of R^2 . The inductance i' is shown in shunt around the armature and contacts of the relay R^2 . Signals sent by reverse currents from Y to X would perform the same work at I and X in the same way, as just described.

It would be inconvenient and expensive 35 to provide transmitting currents at way stations. It is practicable by this system to insert an automatic transmitter in place of the Morse key and operate the neutral or single current relays which, under this condition, are made, in place of the polarized relays to control the recording of signals electro-chemically. In this case the switch S' at I and the switch S at X, for instance, if that is the only station to be reached, are 40 turned to the third position. The lever of transmitter T' is moved forward allowing contacts o' to press on the perforated tape and through the perforations polarized relay R^5 is operated to make and break the 45 main circuit through wire w^1 to main line toward station Y; and from switch s^2 by wire w^5 to contact a' , wire w^4 and neutral relay N' to line toward station X, at which latter station the line is connected to neutral relay N, thence by wire w^2 to contact c of switch S and by wire y to switch s' of transmitter T, then by wire w to switch s of recorder A, and thence to ground. Neutral relay N is now in control of the chemical recording circuit through wire w^{20} , contact c' of switch S, wire w^{21} to chemical tape and recording finger t , wire w^{22} through adjustable resistance r to recording battery u , 55 60

wire w^{23} to front contact of relay N, which relay has inductance i^2 in shunt around its contact points including battery u .

It will be seen that a way wire may be operated either by Morse (as shown by the normal control of sounders H, H', H ^{2} by Morse relays N, N', N ^{2} , respectively), double current automatic, or single current automatic by turning the controlling switches at the stations communicating.

I claim:

1. In telegraphy, the combination of a main line, an automatic transmitter, a local circuit, a polarized relay in said local circuit operated by said automatic transmitter, means controlled by said polarized relay for sending signal impulses into said line, a neutral receiving relay connected in said line, a local circuit, a chemical recorder in said local circuit, and means controlled by said relay for recording signals by said chemical recorder. 75 80 85

2. In telegraphy, the combination of a main line, an automatic transmitter, a local circuit, a polarized relay in said local circuit operated by said automatic transmitter, means controlled by said polarized relay for sending signal impulses into said line, a neutral relay normally connected in said line, a local recorder, a local circuit for recording controlled by said neutral relay, a polarized relay also controlling said recording circuit 90 95 and means for connecting said polarized relay to said main line.

3. In telegraphy, the combination of a recording circuit, a polarized relay controlling said circuit, a neutral relay also controlling said circuit, and a sounder circuit also controlled by said neutral relay. 100

4. In telegraphy, the combination of a line, an automatic transmitter, a polarized relay controlled by said automatic transmitter, means controlled by said polarized relay for sending signal impulses of a single polarity into said main line, means also controlled by said polarized relay for sending signal impulses of reverse polarity into said line, and means at a receiving station for locally recording said single and reverse polarity signals by the same recorder. 105 110

5. In telegraphy a local chemical recording circuit, means for recording by currents of one polarity, and means for sending currents of opposite polarity over said circuit for prevention of marks by local chemical action. 115

In testimony whereof, I have hereunto 120 subscribed my name.

PATRICK B. DELANY.
